UNITED STATES PATENT OFFICE.

WELLINGTON S. JENKINS, OF CLEBURNE, TEXAS.

OIL-BURNER.

SPECIFICATION forming part of Letters Patent No. 795,132, dated July 18, 1905.

Application filed August 17, 1904. Serial No. 221,047.

To all whom it may concern:

Be it known that I, WELLINGTON S. JENKINS, a citizen of the United States, and a resident of Cleburne, in the county of Johnson and State of Texas, have invented a new and Improved Oil-Burner, of which the following is a full, clear, and exact description.

The invention relates to an apparatus for burning heavy oils with the aid of an atomizing-jet. It is particularly adapted to locomotive-work; but it is useful in other connections—for example, with stationary and marine boilers.

A special feature of the present invention lies in a certain novel arrangement causing the oil to flow steadily from the burner in common with the atomizing jet of steam or other fluid, thus producing a regular flame and thorough combustion.

A further feature of the invention lies in the peculiar arrangement of means providing a deflecting-jet applied to the flame from the burner, by means of which said flame may be intensified and directed or controlled.

The invention involves various other features of major or minor importance, all of which will be fully set forth hereinafter and pointed out in the claims.

Reference is had to the accompanying drawings, which illustrate, as examples, two of the preferred embodiments of the invention, in which drawings like characters of reference indicate like parts in the several views, and in which—

Figure 1 is a rear elevation of a locomotive-boiler, showing my invention applied thereto. Fig. 2 is a longitudinal section of the boiler, also showing the burner in operative position.

Fig. 3 is an enlarged plan view of the burner as organized for a vertically-disposed flame.

Fig. 4 is a central longitudinal section of the same. Fig. 5 is a cross-section taken through the nozzle and the atomizing cone or thimble.

Fig. 6 is a fragmentary plan view showing the atomizing cone or thimble as it would appear with its nozzle and plate removed. Fig.

7 is a side elevation of the burner as organized for a horizontally-disposed flame, parts being shown in section in said view. Fig. 8

50 is a plan view of the construction shown in

Fig. 7; and Fig. 9 is a front elevation of the atomizing cone or thimble in the construction shown in Figs. 7 and 8, showing said cone or thimble as it would appear were its nozzle and plate removed from the burner.

55

Referring to Figs. 3 to 6, 12 indicates the body of the burner, which is provided with a longitudinal partition 14, forming two chambers 12^a and 12^b. Of said chambers the chamber 12^a is intended to receive the steam or other atomizing fluid through the pipe 15, and the chamber 12^b is adapted to receive the oil and a quantity of air, as will be hereinafter fully explained, through the pipe 16. The chambers 12^a and 12^b extend forward 60 into an extension 17 of the body 12, the partition 14 having an extension 14^a running into said extension 17, as shown. Fastened, preferably by means of bolts 18, to the extension 17 is a plate-like holder 19, and on top of said holder 19 is located the plate 20 of the nozzle 21, said plate being secured in position also by means of the bolts 18, as shown. The top wall of the extension 17 has an opening 17^a 65 therein, communicating with an opening 19^a 70 in the holder or plate 19. The opening 19^a in turn communicates with a passage or passages 19^b, which lead to an annular groove 19^c, formed in the walls of a central opening or chamber 19^d in the holder 19. Opposite 75 the passage 19^b the holder 19 has a blow-out passage 19^e, and both of the passages 19^b and 19^e are normally plugged, as indicated at 22. By removing one or both of these plugs the 80 passages 19^b and 19^e and the opening or chamber 19^d may be blown out or cleansed of any foreign accumulations. The mixing-thimble 85 23 rests on the extension 17 of the body of the burner, and its central opening is in registry with an opening 17^b in the top of said 90 extension. The mixing-thimble is formed with an annular groove 23^a, registering with the groove 19^c. These registering grooves 19^c and 23^a form an annular steam-chamber. The walls of the opening or chamber 19^d 95 above the groove 19^c are tapered inward, and the upper part of the mixing-thimble 23 is correspondingly tapered, a narrow circular steam-passage 19^f (see Figs. 3 and 4) being left between these two surfaces, owing to 100

bridges or ribs 23^b, formed on the mixing-thimble and engaging the said tapered walls of the opening 19^d. Above the holder or plate 19 the mixing-thimble 23 is formed 5 with oil-outlet openings 23^c, the upper part of the thimble being frusto-conical in shape, as shown. The oil, or the oil and air, as will be hereinafter fully explained, passes up through the opening 17^b from the chamber 12^b and thence into the mixing-thimble 23, from which it passes out through the openings 23^c. Simultaneously the atomizing-steam passes through the narrow circular opening between the parts 23 and 19, 10 assuming a tubular shape, enveloping and completely atomizing the oil. The atomized oil and steam then pass out through the nozzle and burn at the discharge of the same. The nozzle is flared and narrowed toward its 15 discharge, and this peculiar form causes the operation of the burner to result in a partial vacuum, more or less forced, in each end of the nozzle, drawing down into the nozzle the hot air adjacent to the burner and mixing the same with the oil to heat the same and assist 20 in thoroughly atomizing it. The oil is heated in the chamber 12^b, thus increasing the efficiency of the burner, and air is introduced into the oil-supply pipe 16 for the purpose of 25 preventing any deposit therein and also to make the heater more effective and to insure an even feed of oil. This air is admitted before the oil reaches the heater-box and may be either hot or cold; but it is preferably 30 heated, in which condition it results in greater economy of fuel. By admitting the air with the oil as described a regular feed is insured, since the air partly fills the vacuum formed by the steam-jet passing from the mixing- 35 nozzle and prevents erratic oil-flow and consequent explosions due to vibration of the engine in connection with which the burner is used. 21^a indicates a drain-opening at the base of the nozzle 21, which draws back into 40 the burner any oil that may flow out of the nozzle. In order to bring the flame under complete control for raising, lowering, or otherwise regulating the same, I provide means for securing a deflector-jet. This jet is pref- 45 erably of steam and is forced through a nozzle formed by an upward extension 12^a of the case 12, to which is secured a plate 24, this plate being spaced from the extension 12^a to form a steam-chamber 25 and said 50 chamber having a flared outlet 26, discharging horizontally immediately over the nozzle 21. Steam is supplied to the chamber 25 through a pipe 27, mounted on top of the main part of the partition 14 of the burner. By this means 55 the steam-jet directed against the flame may be caused to throw the flame downward to any desired degree, thus bringing the flame under the complete control of the operator and allowing him to meet the various condi- 60 tions under which the burner will have to 65

work, particularly when the burner is applied to locomotives.

Figs. 7, 8, and 9 illustrate a modification different from that shown in Figs. 3 to 6 only in such details as are involved in adapting 70 the burner to a horizontal flame. This form of burner has a body 28 essentially the same as the body 12, to the two chambers of which steam-pipes 15^a and oil-pipes 16^a, respectively, lead. 29 indicates a pipe through which air 75 may be supplied to the oil-pipes 16. The pipe 29 is provided with a strainer 29^a. (See Fig. 7.) The holder-plate 30 is essentially the same as the holder-plate 19 before described, and the nozzle 31 and nozzle-plate 32 80 are also the same essentially as the parts 21 and 20 before described. The nozzle, the holder-plate, and the body of the burner are held secured together by bolts 33, and the mixing-thimble 34 is the same as the mixing-thimble before described, excepting that a single oil-port 34^a only is provided therein. The oil-supply communicates direct with the mixing-thimble 34 through an opening 35, and a deflecting-nozzle 36 communicates with 85 the steam source through a passage 37. The said deflecting-nozzle 36 discharges at the mouth of the burner-nozzle 31 and is fastened on the body 28 of the burner. The operation of this burner is essentially the same 90 as that disclosed in Figs. 3 to 6, the flame being discharged vertically, however, instead of horizontally. This flame may be raised to any inclination by a varying jet through the nozzle 36, as before described. 95

In adapting the invention to locomotive-boilers the arrangement shown in Figs. 1 and 2 is preferably employed. The burner is mounted in position on the boiler by means of lugs, (38 in Figs. 1 and 3 and 39 in Figs. 7 and 8,) by means of which lugs the burner is bolted in place, as shown. If desired, a fire-brick arch 40 and checker-work 41 may be placed in the boiler to increase the heat and to prevent injury to the boiler owing to the intense heat developed at the boiler. In Fig. 1, 42 indicates a valve controlling the oil-pipe 16, to which the oil passes. This valve is operated by means of a long stem 43 and handle 44. The two steam-pipes 15 and 27 (referring 105 to the form of the invention shown in Figs. 3 to 6) pass from a suitable point in the boiler into the main part of the body of the boiler, as before explained, and 45 indicates the air-inlet pipe and strainer which communicates 110 with the oil-pipe 16 the same as the pipe 29 before described. 115

Various changes in the form, proportions, and minor details of my invention may be resorted to at will without departing from the 120 spirit and scope thereof. Hence I consider myself entitled to all such variations as may lie within the terms of my claims.

Having thus described my invention, I claim as new and desire to secure by Letters Patent— 130

1. An atomizing-burner having means for supplying a liquid fuel and an atomizing fluid, a holder having an opening therein and also having an annular groove extending around the walls of said opening, the groove communicating with the atomizing - fluid supply, a centrally-orificed thimble located in said opening in the holder and communicating with the fuel-supply, said thimble having an annular groove matching with the said groove in the holder, and the thimble being spaced from the walls of the opening in the holder at a point between the said grooves and the discharge. 70
2. An atomizing-burner comprising a body having means for supplying a liquid fuel and an atomizing fluid, a holder engaged with the body and having an opening therein, and also having a groove in the walls of the opening, said groove communicating with the atomizing-fluid supply, and a thimble fitted in the opening in the holder and having a central orifice communicating with the fuel-supply, said thimble also having a groove matching with the groove in the holder and the thimble being spaced from the walls of the opening in the holder at a point between said grooves and the discharge. 75
3. An atomizing-burner, comprising means for supplying a liquid fuel and an atomizing fluid, the holder having an opening therein and also having a groove in the walls of the opening, said groove communicating with the atomizing-fluid supply, a thimble located in the opening in the holder and having a central orifice communicating with the fuel-supply, the thimble also having a groove matching with the groove in the holder, and the thimble being spaced from the walls in the opening in the holder at a point between said grooves and the discharge, the discharge portion of the thimble being frusto-conical in form and having outlet-openings in its tapering sides. 80
4. An atomizing-burner comprising a body having means for supplying a liquid fuel and an atomizing fluid, a holder engaged with the body and having an opening therein, and also having a groove in the walls of the opening, said groove communicating with the atomizing-fluid supply, and a thimble located in the opening in the holder and having a centrally-disposed orifice communicating with the fuel-supply, said thimble also having a groove in its outer surface matching with the groove in the holder, the thimble being spaced from the holder at a point between said grooves and the discharge, the discharge end of the thimble being frusto-conical and having discharge-openings in its tapering walls. 85
5. An atomizing-burner, comprising a hollow body formed with two chambers, means for supplying liquid fuel to one of said chambers, and means for supplying an atomizing fluid to the other, a holder having a central opening communicating with the one chamber, and also having another opening and a passage communicating with the other chamber, the walls of said central opening being formed with an inner annular groove communicating with said passage, a thimble having discharge-outlets and communicating with the central opening and formed with an outer annular groove communicating with the said first-named annular groove, the external diameter of the upper part of the thimble being less than the diameter of said central opening, to form an annular passage, and a nozzle to which the thimble leads. 90
6. An atomizing-burner comprising a hollow body formed with two chambers, means for supplying liquid fuel to one of said chambers, and means for supplying an atomizing fluid to the other, a holder having a central opening communicating with the one chamber, and also having another opening and a passage communicating with the other chamber, the walls of said central opening being formed with an inner annular groove communicating with said passage, a thimble having discharge-outlets and communicating with the central opening and formed with an outer annular groove communicating with the said first-named annular groove, the external diameter of the upper part of the thimble being less than the diameter of said central opening, to form an annular passage, and a nozzle to which the thimble leads, the said upper part of said thimble being frusto-conical in form and the adjacent parts of the walls of the central opening being formed in correspondence therewith. 95
7. An atomizing-burner comprising a hollow body formed with two chambers, means for supplying liquid fuel to one of said chambers, and means for supplying an atomizing fluid to the other, a holder having a central opening communicating with the one chamber, and also having another opening and a passage communicating with the other chamber, the walls of said central opening being formed with an inner annular groove communicating with said passage, a thimble having discharge-outlets and communicating with the central opening and formed with an outer annular groove communicating with the said first-named annular groove, the external diameter of the upper part of the thimble being less than the diameter of said central opening, to form an annular passage, and a nozzle to which the thimble leads, said holder having a second passage communicating with said grooves, and each of the passages in the holder being closed at its outer end by a plug, as and for the purpose set forth. 100
8. An atomizing-burner comprising a hollow body having an extension and formed with two chambers, means for supplying liquid fuel to one of said chambers, and means for supplying an atomizing fluid to the other, said extension having a central opening communic- 105
- 110
- 115
- 120
- 125
- 130

cating with the one chamber, and also another opening communicating with the other chamber, a holder provided with a central opening communicating with the corresponding opening of the extension, and with a passage and another opening communicating with said second-named opening of the extension, the walls of the central opening of the holder being formed with an inner annular groove communicating with said passage, a thimble having discharge-outlets communicating with said first-named chamber through both of said mentioned central openings, said thimble having an external annular groove communicating with the annular groove first named, and the external diameter of the upper part thereof being less than the diameter of the central opening of the holder, thus to form an annular passage, and a nozzle to which the thimble leads.

9. An atomizing-burner comprising a hollow body formed with two chambers, means for supplying liquid fuel to one of said chambers, and means for supplying an atomizing fluid to the other, a holder having a central opening communicating with the one chamber, and also having another opening and a passage communicating with the other chamber, the walls of said central opening being formed with an inner annular groove communicating with said passage, a thimble having discharge-outlets and communicating with the central opening and formed with an outer annular groove communicating with the first-named annular groove, the external diameter of the upper part of the thimble being less than the adjacent part of the walls of said central opening, to form an annular passage, and a nozzle to which the thimble leads, having a base and formed with a drain-opening leading to the interior thereof.

10. An atomizing-burner comprising a hollow body having two chambers therein, means for supplying liquid fuel to one chamber, and means for supplying an atomizing fluid to the other, a holder and a thimble formed with adjacent registering annular grooves, the thimble having outlets and communicating with the one chamber, and the said grooves communicating with the other chamber, and a burner-nozzle to which the thimble leads, said holder and the upper part of the thimble being constructed to form between them an annular passage leading from said grooves to said nozzle.

11. An atomizing-burner comprising a hollow body having two chambers therein, means for supplying liquid fuel to one chamber, and means for supplying an atomizing fluid to the other, a holder and a thimble formed with adjacent registering annular grooves, the thimble having outlets and communicating with the one chamber, and the said grooves communicating with the other chamber, and a

burner-nozzle to which the thimble leads; said holder and the upper part of the thimble being constructed to form between them an annular passage leading from said grooves to said nozzle, the latter having a base and provided with a drain-opening leading to the interior thereof.

12. An atomizing-burner comprising a hollow body having two chambers therein, means for supplying liquid fuel to one chamber, and means for supplying an atomizing fluid to the other, a holder and a thimble formed with adjacent registering annular grooves, the thimble having outlets and communicating with the one chamber, and the said grooves communicating with the other chamber, and a burner-nozzle to which the thimble leads, said holder and the upper part of the thimble being constructed to form between them an annular passage having inclined sides and leading from said grooves to said nozzle.

13. An atomizing-burner comprising a hollow body having two chambers therein, means for supplying liquid fuel to one chamber, and means for supplying an atomizing fluid to the other, a holder and a thimble formed with adjacent registering annular grooves, the thimble having outlets and communicating with the one chamber, and the said grooves communicating with the other chamber, and a burner-nozzle to which the thimble leads, said holder and the upper part of the thimble being constructed to form between them an annular passage leading from said grooves to said nozzle, and said body being provided with means for directing a deflector-jet across the discharge-opening of the nozzle.

14. An atomizing-burner comprising a hollow body having two chambers therein, means for supplying liquid fuel to one chamber, and means for supplying an atomizing fluid to the other, a holder and a thimble formed with adjacent registering annular grooves, the thimble having outlets and communicating with the one chamber, and the said grooves communicating with the other chamber, and a burner-nozzle to which the thimble leads, said holder and the upper part of the thimble being constructed to form between them an annular passage leading from said grooves to said nozzle, and said body being provided with an extension having therein a steam-chamber provided with a supply-pipe, a wall of said chamber having therein a discharge-opening adjacent to the discharge-opening of the nozzle.

In testimony whereof I have signed my name to this specification in the presence of two subscribing witnesses.
